UNITED STATES PATENT OFFICE.

MORRIS FOX, OF NORWICH, CONNECTICUT.

DESIGN FOR A BOTTLE.

Application filed May 19, 1927. Serial No. 22,099. Term of patent 14 years.

To all whom it may concern:

Be it known that I, MORRIS Fox, a citizen of the United States, residing at 105 Summit St., city of Norwich, in the county of New London and State of Connecticut, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

MORRIS FOX.
